(57) **CLAIM**

The ornamental design for a phototherapy hair band with stand, as shown and described.

DESCRIPTION

FIG. 1 is a top perspective view of a combined phototherapy hair band with stand;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back perspective view thereof;

FIG. 9 is an assembled view thereof; and,

FIG. 10 is a detailed view taken from line 10 in FIG. 2 thereof.

The evenly spaced broken lines within the bounds of the phototherapy hair band with stand depict portions which form no part of the claimed design. The dash-dot-dash broken lines in FIGS. 2 and 10 identify the boundaries of the FIG. 10 detail view.
